UNITED STATES PATENT OFFICE.

OSCAR P. OSTERGREN, OF NEW YORK, N. Y., AND GUSTAV FAST, OF ORANGE, NEW JERSEY, ASSIGNEES, BY MESNE ASSIGNMENTS, TO COMPOUND CYCLE ENGINE COMPANY, OF NEW YORK, N. Y., A CORPORATION OF NEW YORK.

FUEL-OIL ENGINE.

1,177,890.

Specification of Letters Patent.

Patented Apr. 4, 1916.

Application filed July 22, 1911. Serial No. 639,868.

To all whom it may concern:

Be it known that we, OSCAR P. OSTERGREN and GUSTAV FAST, residing at the city of New York, borough of Brooklyn, State of

- 5 New York, and Orange, in the county of Essex and State of New Jersey, respectively, have invented certain new and useful Improvements in Fuel-Oil Engines, of which the following is a full, clear, and exact description, such as will enable others skilled in the art to which it appertains to make and use the same.

This invention relates to methods of and apparatus for converting heat into work, 15 and, with respect to its more specific features, to motors comprising an internal combustion engine of the constant pressure type.

One of the objects of the invention is the production of a motor of the type described 20 having an increased efficiency.

Another object of the invention is the provision of a practical motor of the type referred to which is of comparatively small weight and size.

25 Another object of the invention is the provision of an efficient motor of the type described which shall be simple in construction and in which relatively few valves are employed.

30 Another object of the invention is the production of a practical motor in which the torque shall be uniform.

Still another object of the invention is the provision of a simple and efficient fuel feeding mechanism for motors of the type described.

Still another object of the invention is the provision of a simple device for efficiently injecting fuel.

40 Other objects will be in part obvious and in part pointed out hereinafter.

The invention accordingly consists in the several steps and the relation and order of one or more of such steps with relation to each of the others thereof, and in the features of construction, combinations of elements and arrangement of parts, which will be exemplified in the method hereinafter disclosed and the construction hereinafter set forth, and the scope of the application of each of which will be indicated in the following claims.

In the accompanying drawings, wherein is shown one of the various possible embodiments of the invention, and in which similar reference characters refer to similar parts throughout the several views, Figure 1 represents an elevation of an apparatus embodying the invention; Fig. 2 is a vertical central cross section through Fig. 1; Fig. 3 is a vertical central cross section through one of the internal combustion engines; Fig. 4 is a vertical longitudinal section through the three cylinders; and Fig. 5 is a section of the fuel pumping mechanism on an enlarged scale.

In motors of the internal combustion type the power of the engine may be measured by the amount and compression of the air which may be utilized to form the explosive mixture. With the same quality of fuel an internal combustion engine will develop power in proportion to the amount of air required to combine therewith to obtain perfect combustion, more air being needed for a larger quantity of fuel, and vice versa. Also, within practical limits, the efficiency of an internal combustion engine is proportioned to the compression to which the air or mixture is subjected before ignition, and, like all engines, the efficiency of the internal combustion is also dependent upon the effective utilization of the expansive force of the motive fluid, increasing the lower the temperature and the pressure are carried before leaving the motor elements. It, therefore, follows that, within the working limits of heat and pressure, the power of an internal combustion engine will be increased by an increase in the amount of air to combine with the fuel; by an increase of the pressure at which ignition is effected, and by a more extended utilization of the inherent expansion energy of the hot motive fluid, and it will be noted that in the engine described herein, the principles of the efficient production of power are exemplified, and that by the arrangement and disposition of the parts together with the principles of operation the engine described is a practical and efficient machine of comparatively small weight, capable of developing great power.

Preparatory to a detailed description of the preferred embodiment of the invention,

it may be stated that though the description in part refers more particularly to internal combustion engines of the constant pressure type, the invention is not to be restricted to such type, as in many important details it will be apparent that other types of internal combustion engines might embody certain aspects of the invention. It is furthermore to be noted that while the description sets forth a preferred form of compressor for initial compression of air, ignition of fuel, scavenging, etc., and a preferred form of fuel pump, as well as other preferred details not now necessary to mention, it will be clear that viewed in certain aspects, the special form described is merely illustrative.

Briefly stated, the embodiment illustrated comprises a plurality of internal combustion engines A and B, which, when regarded as mere engines, are alike in structure and operation. Each of these engines is preferably of the four cycle type, and comprises a cylinder 1, a piston 2, adapted to reciprocate in the cylinder, a connecting rod 3, pivotally joined to the piston, a valve 4, preferably a needle valve, through which fuel is injected into the cylinder, and a valve 5, through which a fluid to support combustion is admitted to the cylinder, in this instance, air, and, as will be noted hereinafter, the valve 5 also serves for the exhaust of the products of combustion from the cylinder. Each internal combustion engine is connected to the usual power transmitting shaft 6, by means of cranks 7 to which the connecting rod 3 is journaled, the cranks of each engine being arranged in identical relation to the shaft, so that the pistons move simultaneously either inward or outward. In the present embodiment the cranks are inclosed in a housing 8, which may contain a supply of oil for lubrication, as is usual in engines of this character.

As before stated, the engines A and B may be of any suitable type of internal combustion engine, but it is preferred to employ internal combustion engines of the constant pressure type, on account of the increased efficiency of such engines over others, and because engines of this type possess special advantages in connection with the other power elements which will now be described.

The character C indicates an expansion motor, which in the preferred embodiment as illustrated, comprises a cylinder 9, and a reciprocating piston 10, connected to the shaft 6 by the usual connecting rod 11, and crank 12, said motor C being preferably located between the engines A and B. The crank of the expansion motor is arranged at an angle of 180° with respect to the cranks 7, so that the piston of the expansion motor moves in its cylinder in directions opposite

to the movement of the pistons 2, the latter moving out as the former moves in and vice versa. In the cylinder of the expansion motor, above the limit of movement of the piston 10, and preferably in the head of the cylinder, are two ports or passageways 13 and 14, connecting the cylinder 9 with the combustion chambers of the engines A and B, respectively, and the valves 5 are located so as to control these passageways, each passageway being thus common to the cylinders A and C, and B and C, respectively, and each valve 5 being common to the same cylinders and controlling passage therebetween. The cylinder of the expansion motor is also provided with an exhaust port 15, adapted to permit the escape into the atmosphere of the contents of the expansion motor cylinder at the completion of the outward stroke of its piston. In the preferred embodiment the piston 10 is of the trunk variety, its depending flange being adapted to uncover the port 15 just prior to the completion of its outward stroke, and to close said port shortly after it begins its inward movement and keep it closed for the full inward stroke. The engines A and B are of the four cycle, constant pressure type, and though the pistons thereof move simultaneously in the same direction, the phases are arranged 360° apart, so that combustion is effected first in one cylinder, then in the other, as the pistons arrive at the inward limit of their stroke, this arrangement, with the expansion motor, resulting in two power impulses for each revolution of the crank shaft.

Enough of the construction has now been described to enable a clear understanding of a portion of the operation to be had, and it will facilitate the comprehension of further description to explain the general operation. Assuming the pistons of the internal combustion engines to be at the upper limit of their movement, and the piston of the engine A to be starting outward on its inlet stroke, the valve 5 governing the passageway 13 will be open and the valve governing the passageway 14 will be held closed by mechanism hereinafter described. The piston of the expansion motor will be at its outer limit and beginning to rise. As it rises, the piston of the engine A descends, and the contents of the cylinder of the expansion motor (in this instance, air) will be compressed through the passageway or port 13 into the cylinder of engine A, the piston of the latter moving outward, and when the stroke in the directions mentioned is completed, air will have been adiabatically compressed in the cylinder of engine A to a degree depending on the relative volumes of cylinders 1 and 9. The diameter of the expansion cylinder and piston is greater than that of either of the internal combustion engines, and the pro-

- portions are such that the pressure in the internal combustion engines upon the completion of the stroke referred to is approximately 100 lbs. The valve 5 of engine A is 5 now closed, and a further compression of air is effected as the piston rises, and when the piston has completed its inward stroke, the air pressure therein is above the igniting point of the fuel employed, at about 750 lbs. 10 Fuel is now injected, and engine A effects its power stroke, the valve 5 still remaining closed. Upon the completion of the power stroke the valve 5 in passageway 13 is opened, and the exhaust of products of combustion 15 remaining in the cylinder are permitted to expand in the cylinder 9 against the piston 10 which is now again at its inner position. Power is thus communicated to the crank shaft by the piston of the expansion motor, and when the port 15 is uncovered, the products, which have been greatly reduced both in pressure and temperature, exhaust into the atmosphere. As the piston 9 descends on its power stroke, the piston 20 of engine A rises and drives out any products of combustion therein, whereupon it is ready for another supply of air. The same cycle of operations is performed by engine B, but each phase being 360° removed from 25 that of engine A, the expansion motor accomplishes an expansion stroke once in every revolution of the crank shaft, the cylinder and piston of the latter operating as a compressor on the return or inward stroke, and compressing its contents alternately, first 30 into the one engine and then into the other, and it will be observed that each passageway 13 and 14 serves both as an exhaust passageway for the products of combustion 35 from the engines and an admission or inlet for air to support combustion, the valves 5 being thus alternately heated by one and cooled by the other, and each valve 5 operating both as an inlet and an exhaust valve 40 for the internal combustion engines.
- In the foregoing description of the operation of the engine, the expansion motor is presumed to have been scavenged in any suitable manner, as by the injection of air 45 from a separate pump, but in the preferred type, as illustrated, the piston of the expansion motor is utilized as the piston of a reciprocating fluid pump, the walls of the cylinder 9 being extended or continued in walls 50 55 forming an inclosed pump chamber 17 on the opposite side of the piston 10, and with which the piston 9 co-operates. In the preferred embodiment the crank 12 is also inclosed in the chamber 17 and a valve 18 is 60 located in the wall of the pump chamber or crank case, preferably a rotary valve, and is so timed as to open when the piston 9 moves on its inward or upward stroke and close when the said piston moves outward. 65 The air sucked in on the upward stroke of
- the piston will be compressed in the crank case on its downward stroke, and a transfer passageway 19 communicating with the crank case and a port 20 in the expansion cylinder, permits the compressed air to 70 enter the latter cylinder at the completion of its expansion stroke, which air drives out through the port 15 any remaining products of combustion in cylinder 9, thus scavenging the expansion cylinder and filling 75 the same with pure air preparatory to the succeeding air compressing stroke of the piston 10. Preferably, the port 20 opens after the exhaust port 15, in order that the pressure in cylinder 9 may be small when 80 the air enters.
- As before stated, the diameter of the expansion motor is greater than that of the internal combustion engines, and its volume is also greater, and it will be clear that on its 85 upward stroke the expansion motor operates as a first stage compressor, and delivers and compresses air into the cylinders of the engines A and B at a comparatively low pressure compared with the ultimate compression in the engines. The engines A and B being of the constant pressure type for only a portion of their stroke, that is, up to the point of cut-off, and the remainder of their power stroke being performed by expansion, the pressure in either at the end of their working stroke is less than the highest compression of air therein, so that the pressure on the piston of the expansion motor is 90 much less per square inch than the highest pressure in the internal combustion engines. Consequently, whether regarded as a compressor or a motor cylinder, the cylinder 9 does not have to withstand pressures as high 95 as those of the internal combustion engines and may accordingly be much lighter in weight. Thus by the two stage compression of air, first by the expansion piston, and then by the piston of the internal combustion engines, a high compression sufficient 100 for ignition is obtained, without the necessity of making the compressor so strong, and consequently so heavy, as to withstand the high pressure, and a greater amount of air is ultimately compressed for combustion. 105 The increased efficiency and lighter weight 110 resulting will be obvious.
- The piston 10 is designed to have practically no clearance at the upper limit of its stroke, and as the passageways 13 and 14 may be short, the quantity of air compressed in the internal combustion engines will be practically constant for each compression stroke. And it will also be noted that by 115 the two stage compressions the volume of highly compressed air at a temperature sufficient to ignite the fuel, is greater than the volume when single stage compression direct from atmospheric pressure is employed, for 120 cylinders of the same size, the heat radiation 125 130

being relatively small, thus preserving a more definite ignition temperature.

Before describing the fuel supply mechanism and the devices employed for the injection of the fuel into the engine, some of the connecting mechanism whereby the several parts operate in prescribed or preferred order will be enumerated. The cranks of the cylinders A, B, and C are connected to the shaft 6, and the mechanisms which operate the fuel pumps, the valves, and the fuel injecting mechanism derive their movement from the crank shaft.

The numeral 21 indicates a gear wheel rotating with the shaft 6, and meshing with a larger gear 22 supported by a horizontal countershaft 23 journaled in bearings on the engine. The rotary air inlet valve 18 which admits air to the crank case is driven from the countershaft through gears 24 and 25, of equal size, secured to the shaft and the rotary valve element respectively, and it will be noted that the valve 18 comprises a rotary, hollow, cylindrical element 26 having diametrically disposed ports 27 adapted to register with similarly disposed ports 28 in the valve case so that the valve 18 is opened every half revolution of the cylindrical element 26, thus permitting air to be drawn into the crank case each time the piston 10 rises. The inlet valve will be closed when the piston 10 descends, thus causing compression in the crank case.

A horizontal cam shaft 29 is journaled in suitable bearings, and extends across the cylinders, and by means of several properly disposed eccentricities 30, motion is communicated to the devices for operating the fuel pump, the fuel valves 4, and the combined admission and exhaust valves 5. Continuous rotation is communicated to the cam shaft from the countershaft by an upright shaft 31 having beveled gears 32 and 33 at either end meshing with bevel gears 34 and 35 on the countershaft and the cam shaft, respectively. By means of straps 36 surrounding certain of the cams 30, and secured to rods 37, vibratory motion is given to the lever arms 38 of oscillating valves 39 controlling the supply and discharge of liquid under pressure to the small cylinders 40, in which pistons 41, connected to the stems 42 of the valves 5 are adapted to reciprocate so as to operate said valves 5. The liquid, such as oil, is supplied from an accumulator through a pipe 43, and is discharged from the cylinder by a pipe 44. As the valves 39 oscillate, the valves 5 are either opened or closed at the proper times to permit the exhaust of the internal combustion engines or the admission of air thereto, the oil under pressure operating to positively accomplish this result and to maintain the valves open or closed, as the case may be, for the required time. In the present embodiment each valve

5 is open during a period of 360° of the stroke and closed for the same period, and the mechanism is so timed that the valves 5 alternately open and close respectively once every two revolutions of the crank shaft 6.

The preferred device for supplying fuel to the internal combustion engines comprises pumping mechanism which delivers the oil fuel to the fuel valves, whence it may be injected into the engines, as hereinafter more particularly described. From any suitable source, oil for fuel is conducted into a reservoir or chamber 45, which is of sufficient capacity to supply oil to separate pumps, one for each internal combustion engine, 80 the reservoir 45 being thus common to the engines. Separate passageways 46 lead the oil by gravity to pump chambers 47, which are continuous with the oil reservoir, except when cut off as hereinafter set forth. Operating in each pump chamber is a pump plunger 48, adapted to reciprocate in said chamber, and force the oil of the chambers through a check valve 49, into pipes 50 and 51, each leading to pipes 52 and 53, through which latter compressed air is forced. In the present embodiment the plunger 48 comprises a rod guided in the walls of the reservoir, suitable packing 54 surrounding the plunger and confined by a cap 55 held in place by a spring 56. One end of the plunger 48 is extended above the top or cover 57 of the reservoir, and preferably terminates in a head 58, between which and the top of the reservoir is interposed a relatively strong spring 59 adapted to raise the plunger on its inlet stroke. Preferably the plunger passes through a cap 60, closing an opening in the top of the reservoir immediately above the packing and cap 55, of sufficient size to permit the removal of the latter when desired.

In order that the delivery stroke of the pump may cause the discharge of a definite and constant amount of oil from the pump chamber, unaffected by any elastic conditions in the reservoir, means are provided for offering a substantially unyielding resistance to the oil on the delivery stroke, except at the discharge opening of the pump, and in the present embodiment this is effected by a valve 61, disposed in the passageway 46, and adapted to open and close said passageway. When the valve is open, oil from the reservoir gravitates into the pump chamber, and a sufficient amount of oil is supplied to the reservoir to fill the passageway and the pump chamber so that when the valve is closed the oil completely fills the pump chamber and the passageway up to and against the valve, thereby providing a pump chamber without any clearance. Under such conditions an amount of oil will be discharged from the pump chamber equal to the displacement of the piston, the device

thus providing for the feed of a fixed amount of oil, dependent only upon the length of the stroke of the plunger.

The valve 61 is provided with a stem 62 passing through the oil reservoir, and out of its upper wall through an elongated guiding bearing 63, and a lever 64, pivoted to the stem 65, extends transversely to the stem, one arm 66 being adapted to contact with the upper face of the head 58 of the pump plunger 48, and another arm 67 terminating in the path of a lug or tooth 68, carried by an oscillatory rod 69, operated through a strap 70 surrounding one of the eccentrics 30 on the cam shaft 29. A spring 71, lighter than the spring 59 of the pump plunger, operates to depress the valve stem 62 and open the valve, the spring 61 being interposed between the inner wall of the oil reservoir and a collar 72 on the valve stem. A plug 73 is provided through which the valve 61 may be removed when required. Pivoted at a suitable point on the engine, in the present instance on the oil reservoir, is a bell-crank 74, one arm being connected to a governor (not shown) and the other arm having a roller 75, coöperating with the face of the oscillatory rod 69 so that it will rotate the arm about its eccentric 30, sufficiently to cause the tooth 68 to disengage the arm 67 of the lever 64 or to entirely escape said tooth as the condition of running may demand. A leaf spring 76 secured to the end of the rod 69 and sliding on a smooth portion of the frame returns the tooth 68 into the engaging line of movement, and causes the rod to follow the retrogression of the roller and remain in contact therewith.

The operation of the mechanism for feeding the fuel as described will now be apparent. As the engine operates the shaft 29 rotates and an up and down reciprocatory motion is imparted to the rod 69. As it rises, the tooth 68 lifts the arm 67, and the spring 71 being lighter than the spring 59, the lever 64 will fulcrum on the head 58 of the pump plunger 48, and the valve 61 will be lifted and close the passageway 46. The lever 64 will then fulcrum at its pivot 65 on the valve stem, and the arm 66 will be depressed, thus forcing the pump plunger down after the valve is closed and delivering oil from the pump chamber through the check valve 49 and into the pipe leading to the cylinder of the internal combustion engine. The pump plunger will be depressed according to the full throw of the eccentric 30 unless the governor causes the bell crank to deflect the rod 69, and disengage the tooth 68 from the arm 67, whereupon the pumping of oil will cease and the plunger will at once return to its upper position under the influence of spring 59, the valve 61 being also immediately opened by spring 71, permitting the pump chamber

to be again filled from the reservoir. The position of the arm 67 with respect to the position of the tooth 68, determines the instant of the beginning of the delivery stroke of the pump, and means are provided for adjusting and fixing said position consisting of an adjustable stop comprising a set screw 77, passing through a bracket or yoke 78 supported on the oil reservoir. The stop is adapted to contact the arm 66, and, with the position of the latter accordingly limits the position of the plunger, as will be apparent. A lock nut 79 is employed to secure the set screw in adjusted position. The stop 77 having been set as desired, the pump will begin its delivery strokes at identical points in the stroke of the engines, the amount of oil discharged being regulated by the cut-off devices operated from the governor driven by the engine.

It will be understood that there is a separate fuel pump for each engine, and separate operating and cut-off devices for each pump, though for convenience the detailed description has been partly set forth in connection with only one of the pumps.

In order to provide air under sufficient pressure to inject the fuel into the cylinders of the internal combustion engines, advantage is taken of the high compression in said cylinders, and a portion of the air supplied for combustion is further compressed to a degree sufficient to force or spray the oil into the engine cylinders against the pressure of compression and at the proper time. To this end a third stage compressor is provided comprising a cylinder 80 located in convenient position to receive a piston or air compressing plunger rod 81, the cylinder 80 being preferably mounted on the head of the expansion motor cylinder, and the plunger being fixed to the piston of the latter motor, passing through a suitable stuffing box on the motor cylinder, and adapted to reciprocate in the cylinder 80. Some clearance in the cylinder 80 is provided, in the present instance by spacing the head 82 of the cylinder from the upper limit of the stroke of the plunger 81, and by making the plunger smaller in cross section than the internal cross section of the cylinder. The amount of clearance may be adjusted by adjusting the plug 83 in the head of cylinder 80. Pipes or passageways 84 and 85 connect the interior of cylinders of the internal combustion engines with the air space in the high stage compressor cylinder 81, and upon the compression stroke of the pistons of the former air is driven through the pipes 84 and 85 into the compressor cylinder, check valves 86 and 87 being suitably located to prevent the return of air through said pipes.

The high stage compressor delivers air into a reservoir 88, through a pipe 89 pro-

vided with a check valve 90 to prevent the return of air to the compressor. The air reservoir 88 comprises a chamber or enlarged pipe connected by the smaller pipes 52 and 53 to the chamber of the fuel valves of each internal combustion engine. The oil from the fuel pump enters the pipes 52 and 53 through a fine opening, and when the needle of the fuel valve is operated to open 10 the valve, the air pressure in the reservoir forces the fuel into the engine cylinders in a fine spray. As it enters it takes fire, on account of the high temperature of the compressed air in the cylinders, but no substantial 15 increase of pressure in the combustion chamber follows, as the piston at once moves on its power stroke and continues to move, the pressure and temperature in the combustion chamber merely changing according to 20 the polytropic law so long as fuel is permitted to enter. When the feed of fuel is cut off, as hereinbefore described, the stroke of the internal combustion engines is completed by the expansion of the hot gases in 25 the cylinders, whereupon one of the valves 5 is opened and the hot gases further expand against the piston of the expansion motor, the piston of the internal combustion engine at the same time rising and driving 30 out the products of combustion from the engine cylinder. It will be understood that the cycles of the internal combustion engines are similar, but phased 360°, as hereinbefore explained.

35 As the pistons 2 rise simultaneously, one compressing air and the other displacing exhaust products, there is a tendency to drive a portion of the contents of the engine cylinders through the pipes 84 and 85 40 into the third stage compressor, the piston 81 of which is then descending. But the third stage compressor is of such dimensions, and the clearance therein is so adjusted, that a pressure is maintained in the 45 cylinder 80 sufficient to prevent the entry of fluid from either internal combustion engine cylinder until the pressure of compression exceeds that of the expanding products, whereupon said compressor will take from 50 the cylinder of higher pressure; viz., the one in which air is being compressed, and no products of combustion will enter the third stage compressor. Owing to the substantial 55 clearance in the third stage compressor, its piston may descend an appreciable amount before its pressure is reduced sufficiently to permit the entry of air from either engine cylinder, but before such a point is reached, the pressure of air in one 60 engine will have exceeded the pressure of exhaust in the other, and further rise of the engine pistons will cause the air to enter cylinder 80 at a pressure sufficient to repel any products of combustion from the other.

65 It will now be perceived that the compress-

ing mechanism supplies air at different pressures, one for combustion and another for fuel injection, and that a portion of the air supplied to the engines is further compressed above that of the air for combustion. It will also be noted that by the arrangement described the compressing mechanism supplies air for combustion to the engines, alternately, and that means are provided for governing the delivery of air to 70 the third stage compressor from the engine cylinders. Assuming the compression for ignition to be about 750 lbs., the initial low compression will be about 100 lbs., and the high or third stage compression will approximate 1,000 lbs., the parts being properly designed to develop these pressures. The fuel valve leading to each engine comprises the usual needle 91 operated by a lever 92 pivoted to a rod 93 operated by eccentric 75 80 85 90 95 100 105 110 115 120 125 130 135 140 145 150 155 160 from a mixture of air and products of combustion from previous power strokes, or as distinguished from engines in which an explosive mixture of air and fuel is introduced and exploded at constant volume. The combined expansion motor and compressor offers a means for the adiabatic compression of the air into the cylinders of the internal combustion engine, thus avoiding the loss of pressure found in those engines where the low compression involves an expansion of the air. In the present embodiment the air is not only adiabatically compressed to the low pressure in the cylinders of the internal combustion engines, but is further adiabatically compressed by the pistons of the latter engines. It will, of course, be understood that the word "adiabatic" is used in a sense as distinguished from any changes of temperature of the air due to the heating of the compressor or engine elements from the heat of combustion. While it is preferred to compress pure air in the cylinders of the internal combustion engines, as making for greater efficiency, it is to be understood that viewed in some aspects a mixture of air and a neutral gas or vapor may be employed, and in the latter case a sufficient amount of air to combine with the fuel should be used. It will be noted, therefore, that the method of extracting the work from the heat involves, first, a compression of the air to a degree producing a temperature below the igniting point of the fuel to be consumed, then further compressing the compressed air to such a degree as to produce a temperature above the igniting point of such fuel. The fuel for combustion is then gradually introduced into the highly compressed air, and during its introduction combustion is effected on account of the temperature of the air, and its continued introduction into the cylinder causes the movement of the piston under a constant pressure until the supply of fuel is cut off, as hereinbefore described. In order to utilize as much as possible of the heat in the excess products of combustion, after the supply of fuel is cut off the hot products are allowed to expand thereafter in the cylinder of the internal combustion engine, and a further expansion takes place in the cylinder of the expansion motor.

By separating the power strokes of the internal combustion engines and by providing suitable intervals between the power strokes of said engines and of the compression motor, together with the arrangement of cranks as hereinbefore set forth, a uniform torque is given, and a substantially uniformly balanced engine is assured, the weights participating to some extent in securing this result.

By the arrangement described, an engine is provided in which comparatively few

valves are employed, the inlet and exhaust valves of the internal combustion engines being identical, and the exhaust valves of the internal combustion engines being identical with the admission valves of the expansion motor.

The operation of the engine as a whole will be apparent from the above description. Assuming the cylinder 9 to contain pure air, and the piston 10 to be at the limit of its outward stroke, one of the engines A or B will be about to execute its power stroke and the other will be about to take in a fresh supply of air. Let us assume the engine A to be about to effectuate its power stroke and the engine B to be about to take in air. The valve 5 of engine B will be opened and the valve 5 of engine A will be held closed, and when the fuel is injected into the engine A its piston 2 will be forced down. The piston 10 will rise and compress air through the passageway 14 to a comparatively low pressure in the engine B. At a certain point in the stroke of engine A the supply of fuel is cut off, and further movement is effected by the expansion of the gases of combustion. When the three pistons shall have reached the limit of their outward stroke the valve 5 of engine A will be opened and that of engine B closed, whereupon a further expansion of the hot products of combustion will result in causing a power impulse of the piston 10, and when the pistons shall have reached the limit of their outward stroke the engine B will be in position for the injection of fuel, and the same operation as before will take place in connection with said engine B. As the pistons 2 rise, one displacing the products of combustion and the other compressing from low compression, fluid from either cylinder will be prevented from entering the third stage compressor until the pressure in the engine containing substantially pure air shall have exceeded that in the engine which is exhausting, whereupon further compression of the air will result in forcing a portion thereof into the third stage compressor, whose piston has descended sufficiently by this time to permit the entry of such air through one of the check valves 86 or 87, as the case may be. As the piston of the third stage compressor rises, air will be compressed to a pressure exceeding the highest pressure in the internal combustion engines and stored in the reservoir 88, wherefrom it may be utilized to inject the fuel through the fuel valve at the proper times, as hereinbefore described. It will be understood that the dimensions of the several engines and of the third stage compressor are such that the difference in pressure referred to in the description may result. As an example of the relative pressures which may be utilized, it may be

stated that the low compression caused by the rise of the piston 10 may be about 100 lbs. in the internal combustion engine cylinders. This pressure of air is increased to 5 say 750 lbs. by compression in the engine cylinders, and the air forced into the third stage compressor may be compressed thereby to a 1000 lbs.

It will be noted that this engine provides 10 a larger volume of compressed air having a relatively small surface at the critical period of the cycle, that is, when the pressure and temperature are high, so that the radiation of heat per unit volume is small 15 and less than for the same quantity of air confined in a space having a greater superficial extent. By making the pistons 2 of the engines concave, as shown, the unit area of the radiating surface is further decreased. 20 Thus, by the above described embodiment will be accomplished, among others, the objects hereinbefore referred to.

As many changes could be made in carrying out the above method, and in the above 25 construction, and many apparently widely different embodiments of this invention could be made without departing from the scope thereof, it is intended that all matter contained in the above description or shown 30 in the accompanying drawings shall be interpreted as illustrative and not in a limiting sense. It is also to be understood that the language used in the following claims is intended to cover all of the generic and 35 specific features of the invention herein described and all statements of the scope of the invention, which, as a matter of language, might be said to fall therebetween.

Having described our invention, what we 40 claim as new and desire to secure by Letters Patent is:

1. In an apparatus of the character described, in combination, a cylinder, a piston adapted to reciprocate therein, means providing for the inlet of a fluid to one end of the cylinder as the piston moves in one direction, ports in the cylinder at the end of said stroke, a port in the cylinder intermediate the limits of the piston movement, and 50 means whereby the movement of the piston in the opposite direction transfers fluid into the opposite end of the cylinder and alternately through said first-mentioned ports.

2. In an apparatus of the character described, in combination, a cylinder, a piston adapted to reciprocate therein, means providing for the inlet of a fluid to one end of the cylinder as the piston moves in one direction, ports in the cylinder at the end of 55 said stroke, a port in the cylinder intermediate the limits of the piston movement, and means whereby the movement of the piston in the opposite direction transfers fluid into the opposite end of the cylinder and out of

the cylinder through two of said first-mentioned ports alternately. 65

3. In an apparatus of the character described, in combination, a cylinder, a crank case communicating with one end thereof, a piston adapted to reciprocate in said cylinder, 70 a valve in the crank case adapted to permit air to enter the case and prevent its emergence, a passageway adapted to establish communication between the crank case and the cylinder on the opposite side of the piston at the end of the piston stroke in one direction, the piston being adapted to close the passageway during its stroke in one direction, an exhaust port in the cylinder intermediate the limits of the piston movement, combined inlet and discharge ports at the end of the cylinder remote from the exhaust port, valves controlling the latter ports, a plurality of combustion cylinders, and means for controlling said valves to 80 discharge the contents of the cylinder alternately through said ports into the combustion cylinders as the piston is operated.

4. In an apparatus of the character described, in combination, a plurality of internal combustion engines, a combined pump and motor comprising a cylinder, 90 passageways connecting said cylinder and said engines, and a combined inlet and exhaust valve for each engine disposed to control said passageways.

5. In an apparatus of the character described, in combination, a plurality of internal combustion engines of the four cycle type in which similar phases of the cycles 100 are substantially 360° apart, a combined pump and motor comprising a cylinder, and passageways connecting said cylinder and said engines, each engine comprising a common valve for the inlet of air and the exhaust of products of combustion disposed to control said passageways, respectively. 105

6. In an apparatus of the character described, in combination, a plurality of internal combustion engines of the four cycle type in which similar phases of the cycles 110 are substantially 360° apart, each engine comprising a common valve for the inlet of air and the exhaust of products of combustion, and a combined pump and motor 115 cylinder connected to the passageway governed by the valves, and means for causing the valves of one engine to remain open during a period of substantially 360° of the stroke and the other valve to remain closed 120 during the same period.

7. In an apparatus of the character described, in combination, a plurality of internal combustion engines of the four cycle type in which similar phases of the cycles 125 are substantially 360° apart, each engine comprising a common valve for the inlet of air and the exhaust of products of com-

bustion, and a combined pump and motor cylinder connected to the passageway governed by the valves, and means positively holding the valve of one engine open during a period of substantially 360° of the stroke and the other valve closed during the same period.

8. In an apparatus of the character described, in combination, a plurality of internal combustion engines of the four cycle type in which similar phases of the cycles are substantially 360° apart, each engine comprising a common valve for the inlet of air and the exhaust of products of combustion, a combined pump and motor cylinder connected to the passageways governed by the valves, and means adapted to cause each of said valves to alternately open and close during every two revolutions of the crank shaft.

9. In an apparatus of the character described, in combination, an internal combustion engine comprising a cylinder and piston, an expansion motor comprising a cylinder and piston, a passageway connecting the cylinders, a valve controlling the passageway, and means to operate the valve so that the exhaust of the engine discharges into the expansion motor and the expansion motor pumps air into the engine through said passageway.

10. In an apparatus of the character described, in combination, an internal combustion engine comprising a cylinder and piston, an expansion motor comprising a cylinder and piston, an air pump, a passageway connecting the cylinders, a separate passageway connecting the expansion motor cylinder and the pump chamber, means whereby the exhaust of the engine energizes the expansion motor, and means whereby the pump is operated to supply the motor with air.

11. In an apparatus of the character described, in combination, a plurality of internal combustion engines, air compressing mechanism, means whereby the air compressing mechanism supplies air for combustion to the engines alternately, and means whereby a portion of the air supplied to each engine is further compressed to a pressure above that of the air for combustion.

12. In an apparatus of the character described, in combination, a plurality of internal combustion engines, fuel valves, air compressing mechanism, means whereby the air compressing mechanism supplies air for combustion to the engines alternately, and means whereby a portion of the air supplied to each engine is further compressed to a pressure sufficient to feed the fuel into the combustion chamber.

13. In an apparatus of the character described, in combination, a plurality of in-

ternal combustion engines, an air reservoir, means whereby air for combustion is supplied to the engines alternately, means whereby a portion of the air supplied to each engine is delivered therefrom into the reservoir, and means for maintaining the pressure in the reservoir above that of the pressure in either engine.

14. In an apparatus of the character described, in combination, a plurality of internal combustion engines, an air compressor adapted to be supplied from the combustion chamber of either engine, and means whereby the compressor is adapted to take air from the engines alternately.

15. In an apparatus of the character described, in combination, a plurality of internal combustion engines, an air reservoir, means whereby air for combustion is supplied to the engines alternately, means whereby a portion of the air supplied to each engine is delivered therefrom into the reservoir, and means for governing the delivery.

16. In an apparatus of the character described, in combination, an internal combustion engine, an expansion cylinder, an air reservoir, means whereby the internal combustion engine exhausts into the expansion cylinder, means whereby the expansion cylinder supplies air for combustion to the internal combustion engine, means whereby a portion of the air supplied to the internal combustion engine is delivered therefrom into the reservoir, and means for compressing the air in the reservoir above the pressure in the internal combustion engine.

17. In an apparatus of the character described, in combination, an internal combustion engine, an expansion cylinder and piston, an air reservoir, a high stage compressor comprising a piston movable with the expansion piston, means whereby the internal combustion engine exhausts into the expansion cylinder against its piston, means whereby the expansion cylinder and piston operate to supply air for combustion to the internal combustion engine, means whereby a portion of the air supplied to the internal combustion engine is delivered into the high stage compressor, and means whereby the latter delivers air into the reservoir.

18. In an apparatus of the character described, in combination, an internal combustion engine, a fuel inlet, an expansion cylinder and piston, an air reservoir, a high stage compressor comprising a piston movable with the expansion piston, means whereby the internal combustion engine exhausts into the expansion cylinder against its piston, means whereby the expansion cylinder and piston operate to supply air for combustion to the internal combustion engine, means whereby a portion of the air

supplied to the internal combustion engine is delivered into the high stage compressor, means whereby the latter delivers air into the reservoir, and means adapted to deliver 5 the highly compressed air through the fuel inlet.

19. In an apparatus of the character described, in combination, an internal combustion engine, an expansion motor adapted to 10 receive the exhaust from the internal combustion engine, a third stage compressor, means whereby the internal combustion engine and the expansion motor operate to compress air in two stages into the third 15 stage compressor, an air reservoir, and means whereby the latter compressor delivers air into the reservoir.

20. In an apparatus of the character described, in combination, an internal combustion engine, a fuel inlet, an expansion motor adapted to receive the exhaust from the internal combustion engine, a third stage compressor, means whereby the internal combustion engine and the expansion motor operate to compress air in two stages into the third stage compressor, an air reservoir, means whereby the latter compressor delivers air into the reservoir, and means adapted to deliver the highly compressed air 30 through the fuel inlet.

21. In an apparatus of the character described, in combination, a plurality of internal combustion engines, an expansion motor adapted to receive the exhaust of the 35 internal combustion engines, means whereby the expansion motor alternately supplies air at comparatively low pressure to the internal combustion engines, means whereby the internal combustion engines compress said air 40 to a higher pressure, a reservoir, and means whereby a portion of the air of higher pressure is further compressed into the reservoir to a pressure exceeding the highest compression in the internal combustion engine.

45 22. In an apparatus of the character described, in combination, a plurality of internal combustion engines, fuel inlets therefor, an expansion motor adapted to receive the exhaust of the internal combustion engines, means whereby the expansion motor alternately supplies air at comparatively low pressure to the internal combustion engines, means whereby the internal combustion engines compress said air to a higher 50 pressure, a reservoir, means whereby a portion of the air of higher pressure is further compressed into the reservoir to a pressure exceeding the highest compression in the internal combustion engines, and means 55 for supplying the highly compressed air to the fuel injectors.

60 23. An apparatus of the character described, comprising, in combination, a plurality of internal combustion engines, an

expansion motor, an air pump, ports connecting the combustion chambers of the internal combustion engines and the cylinder of the expansion motor, valves controlling the ports, means for operating the valves to permit the products of combustion to expand alternately into the motor, and means whereby the air pump scavenges the expansion motor cylinder at the end of its expansion stroke.

65 24. An apparatus of the character described, comprising, in combination, a plurality of internal combustion engines, an expansion motor, an air pump, ports connecting the combustion chambers of the internal combustion engines and the cylinder of the expansion motor, valves controlling the ports, means for operating the valves to permit the products of combustion to expand alternately into the motor, and means whereby the air pump fills the expansion 70 motor cylinder with air at the end of its expansion stroke.

75 25. An apparatus of the character described, comprising, in combination, a plurality of internal combustion engines, an expansion motor, an air pump, ports connecting the combustion chambers of the internal combustion engines and the cylinder of the expansion motor, valves controlling the ports, means for operating the valves to permit the products of combustion to expand alternately into the motor, and means whereby the air pump scavenges the expansion 80 motor cylinder and fills it with air at the end of its expansion stroke.

85 100

26. An apparatus of the character described, comprising, in combination, a plurality of internal combustion engines, a combined expansion motor and pump comprising a cylinder and piston, passageways 105 leading from a point in the cylinder beyond the limit of the piston stroke in one direction to the combustion chambers of the internal combustion engines, respectively, an air inlet port in said cylinder below the limit 110 of the piston stroke in the opposite direction, means whereby the power strokes of the combined expansion motor and pump alternate with those of the internal combustion engines, means adapted to establish 115 communication between the opposite ends of the cylinder of the combined expansion motor and pump when the latter completes its power stroke, and means to close one of said passageways during said stroke.

120 27. An apparatus of the character described, comprising, in combination, a plurality of internal combustion engines having their phases 360° apart, a combined expansion motor and pump comprising a cylinder and piston, passageways leading from a point in the cylinder beyond the limit of the piston stroke in one direction to the 125

- combustion chambers of the internal combustion engines, respectively, an air inlet port in said cylinder below the limit of the piston stroke in the opposite direction, 5 means whereby the power stroke of the combined expansion motor and pump alternate with those of the internal combustion engines, means adapted to establish communication between the opposite ends of the cylinder of the combined expansion motor and pump when the latter completes its power stroke, and means to close one of said passageways during said stroke.
28. An apparatus of the character described, comprising, in combination, a plurality of internal combustion engines, a combined expansion motor and pump comprising a cylinder and piston, passageways leading from a point in the cylinder beyond 10 the limit of the piston stroke in one direction to the combustion chambers of the internal combustion engines, respectively, valves controlling said passageways, an air inlet port in said cylinder below the limit 15 of the piston stroke in the opposite direction, means whereby the power stroke of the combined expansion motor and pump alternate with those of the internal combustion engines, means adapted to establish communication between the opposite ends of the cylinder of the combined expansion motor and pump when the latter completes its power stroke, and means to positively close one of said valves and hold the 20 other open during said stroke.
29. An apparatus of the character described, comprising, in combination, a plurality of internal combustion engines, a combined expansion motor and pump comprising a cylinder and piston, passageways leading from a point in the cylinder beyond 25 the limit of the piston stroke in one direction to the combustion chambers of the internal combustion engines, respectively, an air inlet port in said cylinder below the limit 30 of the piston stroke in the opposite direction, a shaft, parallel cranks thereon connected with the pistons of the internal combustion engines, respectively, another crank on said shaft disposed at 180° with respect to said first-mentioned crank and connected to the piston of the combined 35 motor cylinder and pump, means adapted to establish communication between the opposite ends of the cylinder of the combined expansion motor and pump when the latter completes its power stroke, and means to close one of said passageways during said stroke.
30. An apparatus of the character described, comprising, in combination, a plurality of internal combustion engines of the constant pressure type, an expansion motor adapted to receive the exhaust of the 40 internal combustion engines, a reciprocating pump having its piston identical with that of the expansion motor, and means whereby said pump presses pure air at a relatively low pressure into the cylinders of the internal combustion engines. 45
31. In an apparatus of the character described, in combination, a plurality of internal combustion engines, an expansion motor, means for causing the engines and motor to operate in unison, and means for utilizing the cylinder of the expansion motor to initially compress air at low pressure alternately into the cylinders of the internal combustion engines. 50
32. In an apparatus of the character described, in combination, a plurality of internal combustion engines, fuel inlets therefor, an air reservoir, means permitting the passage of fluid from either engine into the reservoir, means adapted to maintain a pressure in the reservoir greater than that in either engine, and means permitting air from the reservoir to feed the fuel through the inlets. 55
33. In an apparatus of the character described, in combination, a plurality of internal combustion engines, fuel inlets therefor, an air reservoir, means whereby air for combustion is supplied to the engines alternately, means whereby a portion of the air supplied to each engine is delivered therefrom into the reservoir, means for governing the delivery, and connections between the air reservoir and the fuel inlets. 60
34. In an apparatus of the character described, in combination, a plurality of internal combustion engines having their similar phases 360° apart, an expansion cylinder and piston, an air reservoir, a high stage compressor comprising a piston movable with the expansion piston, means whereby the internal combustion engines exhaust into the expansion cylinder, means whereby the expansion cylinder and piston operate to supply air for combustion to the internal 65 combustion engines, means whereby a portion of the air supplied to the internal combustion engines is delivered into the high stage compressor, means whereby the latter delivers air into the reservoir, and connections between the reservoir and the fuel inlets of the internal combustion engines. 70
35. A motive unit comprising, in combination, a pair of internal combustion engines of the constant pressure type, a reciprocating expansion motor and pump having a common piston, common exhaust and inlet passageways connecting the engines and the expansion motor and pump, respectively, a high stage compressor, passageways connecting the compressor and the fuel inlets of the engines, and operating devices associated with the aforesaid parts where- 75

by the air for combustion will be compressed in the engines above the ignition temperature of the fuel, and air delivered through the fuel inlets during the high pressure in the engines.

36. In an apparatus of the character described, in combination, a plurality of internal combustion engines, a combined expansion motor and air compressor adapted to 10 receive the exhaust of the engines and compress air for combustion, a high stage compressor, an air reservoir connected thereto and to the fuel inlet of each engine, passageways leading from each engine to the high 15 stage compressor, and check valves in the passageways and in the connection between the compressor and reservoir.

37. In an apparatus of the character described, in combination, a driving shaft, a 20 pair of internal combustion engines with their similar phases 360° apart, connected to said shaft, a cylinder and piston disposed between said engines, the piston being connected to said shaft, means whereby the 25 exhaust of the internal combustion engines expands in the intermediate cylinder, means whereby the intermediate cylinder is filled with air on its return stroke, a high stage compressor cylinder, a piston therefor connected to the intermediate piston, an air reservoir, passageways connecting the engine cylinders with the cylinder of the high stage compressor, valves permitting flow from the engines to the compressor cylinder through 30 said passageways and preventing return flow, a passageway governed by a valve and adapted to lead air from the compressor to the reservoir and prevent its return, and passageways connecting the reservoir with 35 the fuel inlet passageway of each engine.

38. In an apparatus of the character described, in combination, a plurality of internal combustion engines having their similar phases 360° apart, a combined expansion 40 motor and pump comprising a cylinder and piston, common exhaust and inlet passageways connecting the engine cylinders and the cylinder of the expansion motor and pump, common inlet and exhaust valves 45 governing said passageways, exhaust and air inlet ports in the cylinder of the expansion motor and pump governed by the piston and adjacent the end of its motor stroke, a passageway connecting the interior of the expansion motor and pump cylinder around its piston through the air inlet port in said cylinder, and an air inlet valve in said cylinder below the piston.

39. In an apparatus of the character described, in combination, a plurality of internal combustion engines, an expansion motor, means for causing the engines and motor to operate in unison, and means for utilizing the expansion motor to initially compress

air alternately into the cylinders of the internal combustion engines, comprising a plurality of ports in the expansion motor cylinder at one end of its stroke, an exhaust port at the opposite end of its stroke, valves adapted to control passage through the first-mentioned ports, and means adapted to positively operate said valves.

40. In an apparatus of the character described, in combination, a plurality of internal combustion engines, an expansion motor, means for causing the engines and motor to operate in unison, means for utilizing the expansion motor to initially compress air alternately into the cylinders of the internal combustion engines, comprising a plurality of admission ports in the expansion motor cylinder at one end of its stroke, a port at the opposite end of its stroke adapted to discharge the expansion motor cylinder on the same side of its piston as the admission ports, valves adapted to control passage through said first-mentioned ports, and means adapted to positively operate said valves.

41. In an apparatus of the character described, in combination, a plurality of internal combustion engines, an expansion motor comprising a cylinder, a piston adapted to reciprocate therein, means for causing said engines and motor to operate in unison, and means for utilizing the expansion motor to initially compress air alternately into the internal combustion engines, comprising means providing for the inlet of a fluid to one end of said cylinder as its piston moves in one direction, ports in said cylinder at the end of said stroke, and means whereby the movement of said piston in the opposite direction transfers fluid into the opposite end of said cylinder and alternately through said ports.

42. In an apparatus of the character described, in combination, a plurality of internal combustion engines, an expansion motor comprising a cylinder, a piston adapted to reciprocate therein, means for causing said engines and motor to operate in unison, and means for utilizing the expansion motor to initially compress air alternately into the internal combustion engines, comprising means providing for the inlet of a fluid to one end of said cylinder as its piston moves in one direction, ports in said cylinder at the end of said stroke, a port in said cylinder intermediate the limits of said piston movement, and means whereby the movement of said piston in the opposite direction transfers fluid into the opposite end of said cylinder and alternately through said first-mentioned ports.

43. In an apparatus of the character described, in combination, a plurality of internal combustion engines, an expansion motor,

means for causing the engines and motor to operate in unison, means for utilizing the expansion motor to initially compress air alternately into the cylinders of the internal combustion engines, and means whereby a portion of the air supplied to each engine is further compressed to a pressure above that of the air for combustion.

44. In an apparatus of the character described, in combination, a plurality of internal combustion engines, an expansion motor, an air reservoir, means for causing the engines and motor to operate in unison, means for utilizing the expansion motor to initially

compress air alternately into the cylinders 15 of the internal combustion engines, means whereby a portion of the air supplied to each engine is delivered therefrom into said reservoir, and means for maintaining the pressure in the reservoir above that of the compression in either engine. 20

In testimony whereof we affix our signatures, in the presence of two witnesses,

OSCAR P. OSTERGREN,
GUSTAV FAST.
